MERCURY SWITCH

Harlie O. Putt, Elkhart, Ind., assignor to The
Adlake Company, Elkhart, Ind., a corporation
of Illinois

Application July 5, 1932, Serial No. 620,798

4 Claims. (Cl. 200—97)

This invention relates to mercury switches, and has for its principal object to facilitate the making of small openings for the passage of fluids to accurately time the operation of the 5 switches.

The drawing shows the invention in connection with one type of mercury switch relay, in which:

Fig. 1 is a vertical section through the relay 10 with the magnet energized;

Fig. 2 is a similar view with the magnet deenergized;

Fig. 3 is an enlarged sectional view of one end of the displacer;

Fig. 4 is a plan view of the same; and

Figs. 5 and 6 are side elevation and plan view of a plug used to adjust the size of a passage in the displacer.

But these specific drawings and the corresponding specific description are used for the purpose of illustration and disclosure only, as other applications within the spirit of the invention will occur to those familiar with this art.

The switch envelope 10 is a cylindrical glass tube, with a pinch seal 11 at the top and a flat base 12 in which the lead-in conductors 13 and 14 are sealed. The conductor 14 extends a considerable distance into the envelope, and is enclosed within a glass sleeve 15 fused to the base. The conductors are equipped with electrodes 16 and 17, respectively. Within the tube is a charge of mercury 18, a displacer 19, two non-magnetic springs 20 which cushion the movements of the displacer in shipping and handling, and also a gas fill, such as hydrogen, helium, and the like.

The displacer is made of Swedish iron, or other magnetic material, so as to be shifted by the attraction of a magnet comprising a solenoid 21, wound on a spool 22, mounted between the arms of a yoke 23 and held by iron sleeves 24, which also serve as mountings for the mercury tube, which is held against movement by a non-magnetic coil 25. The displacer is, generally speaking, a hollow cylinder having narrow flanges 26 at its ends cut away to permit free flow of the fluid. The bore 27 is substantially cylindrical to near the top, where the wall takes the form of the frustum of a cone 28 adjacent to which is a plug 29, of burnt asbestos fiber, hair, steel wool, or the like. The top is provided with a narrow passage to permit restricted flow of gas into and out of the bore

in response to a movement of the displacer with respect to the magnet.

For example, when the magnet is deenergized the displacer drops from the position shown in Fig. 1 toward the position shown in Fig. 2, 60 causing the gas within the bore of the displacer above the mercury to be compressed, with the result that the mercury is prevented from rising above the sleeve 15 to close the circuit with the electrode 17 until the desired delay has 65 elapsed, the time being consumed by restricting the flow of gas from the interior of the displacer to the exterior.

In many types of switches the passage for gas must be made very accurately to fractions 70 of a thousandth of an inch, and the processes heretofore used for that purpose have been relatively expensive. According to this invention a relatively large hole 30 is bored through the wall of the displacer. A cylindrical plug 75 31, of a size to fit tightly in that hole, is first prepared and then cut or ground away at one side, 32, at an angle to the axis of the plug. In other words, a wedge-shaped strip is cut 80 away. The plug is then inserted in the opening 30 and pressed or driven until the clearance between the face 32 and the adjacent wall of the opening 30 is the size required under the conditions that the device is to operate. In practicing this method the displacers are made 85 by a standard test, and the plugs 31 accurately set before the displacers are sealed in the envelope.

It is much easier to fit a relatively large plug 90 in a hole than to form a very small hole to accurate size. Having fitted the plug in the hole and provided it with a varying cross-section, nothing remains but to press or drive the plug back and forth until the orifice is at the exact 95 size required.

As an example: With a displacer 1-1/2" long, 1-3/64ths" inside and 9/32nds" outside diameter, I use a hole 1/16" in diameter and a plug 1/16" in diameter and 3/16" long, tapered as 100 shown to 3/64" thickness.

I claim as my invention—

1. For use in a mercury switch of the class described, a hollow body having a large opening for liquid and a small opening for gas, the latter opening consisting of clearance between 105 the wall of the opening, and a smooth-faced cylindrical plug tightly fitted in the opening and having a portion cut away at an angle to its axis.

2. For use in a mercury switch of the class 110

described, a hollow body having a large opening for liquid and a small opening for gas, the latter opening consisting of clearance between the wall of the opening, and a smooth-faced 5 cylindrical plug tightly fitted in the opening and having a flattened side face at an angle to its axis.

3. For use in a mercury switch of the class described, a hollow body having a large opening 10 for liquid and a small opening for gas, and means associated with said latter opening for varying its effective size, said means including a smooth-walled plug which progressively and

substantially uniformly changes the size of the opening as it is driven into the opening.

4. In combination with a time delay mercury switch, a wall adapted to separate two bodies of gas of unequal pressure, said wall having an 80 aperture through which gas may pass, and means for varying the effective size of the aperture, said means including a smooth-walled plug which progressively and substantially uniformly changes the size of the opening as it 85 is driven into the opening.
